UNITED STATES PATENT OFFICE.

LAFAYETTE PICKERING, OF COLUMBUS, OHIO, ASSIGNOR TO THE COLUMBUS DENTAL MANUFACTURING COMPANY, OF COLUMBUS, OHIO, A CORPORATION OF OHIO.

CARDING DEVICE FOR ARTIFICIAL TEETH.

Application filed September 13, 1924. Serial No. 737,537.

To all whom it may concern:

Be it known that I, LAFAYETTE PICKERING, a citizen of the United States, residing at Columbus, in the county of Franklin and 5 State of Ohio, have invented certain new and useful Improvements in Carding Devices for Artificial Teeth, of which the following is a specification.

This invention relates to an improved 10 carding device for effecting the removable mounting for artificial teeth upon a suitable form of base for the purpose of holding the teeth incident to their shipping or display.

The primary object of the invention 15 consists in the provision of an improved mounting by which artificial teeth can be securely and removably connected upon a suitable form of base, and to permit this object to be carried out in such a manner as to avoid 20 injury to the teeth when applied to or removed from the base, to securely hold the teeth against accidental displacement while on the base, to permit of their individual removal or application with respect to the 25 base and to provide a novel form of securing means constructed for convenient operation, simple and economical to manufacture and embodying other advantageous features of design, construction and operation to be 30 hereinafter pointed out.

With these and other objects in view, as will appear as the description proceeds, the invention consists in the novel features of construction, combinations of elements and 35 arrangements of parts hereinafter to be fully described and pointed out in the appended claims.

In the accompanying drawing:

Figure 1 is a front elevation of a preferred 40 form of the mounting comprising the present invention,

Figure 2 is a vertical section taken on the line 2—2 of Figure 1,

Figure 3 is an edge elevation of the 45 mounting,

Figure 4 is a cross-section on the line 4—4 of Figure 1,

Figure 5 is a similar view disclosing a slightly modified form of the holding head,

Figure 6 is a side elevation showing a further modified form of the invention,

Figure 7 is a section on the line 7—7 of Figure 6,

Figure 8 is a front elevation of a further 55 modification,

Figure 9 is a vertical sectional view on the line 9—9 of Figure 8,

Figure 10 is a front elevation of a still further modified form, and

Figure 11 is a section on the line 11—11 of 60 Figure 10.

In previous forms of holders or mountings for artificial teeth it has been proposed to retain the teeth in place by the provision of fixed studs projecting from the base of the 65 mounting and arranged to be received within longitudinal grooves provided in the lingual surface of the teeth and in connection with this structure resilient means have been provided whereby when the teeth are 70 mounted on the holding studs spring pressure is applied to the teeth so as to create a friction between the walls of the grooves and the complementary surface of the studs to prevent the teeth from becoming accidentally 75 disengaged with the holding studs. In some instances this pressure is exerted outwardly upon the teeth so as to force the latter away from the base of the mounting and in other instances this arrangement is 80 reversed and the spring pressure is applied inwardly upon the teeth. In either event, however, considerable pressure is applied to the teeth at all times while they are retained upon the holding studs. This structure 85

holds the teeth in applied positions and effectually prevents accidental removal of the teeth from the mountings. These teeth are formed from a suitable porcelain composition and possess a hard, tough molecular 90 structure, nevertheless, in the event they are roughly handled or if the spring pressure exercised thereon is too great, the walls of the securing grooves are apt to crack or fracture to an extent wherein the teeth are 95 destroyed or rendered unfit for actual use. Therefore, the present invention is directed chiefly to the provision of an improved form of mounting wherein a structure is provided for effectually preventing the accidental removal of the teeth while applied to the mounting, and an arrangement provided 100 whereby injury to the teeth, by reason of the mounting, is effectively precluded.

To this end, the form of the invention disclosed in Figures 1 to 4 inclusive consists of a mounting 1 comprising a base 2 of wood or metal as the case may be, which may be provided with an ornamental plush exterior surface if desired. Secured at regular in- 110

2
tervals in the mounting is a plurality of studs 3, which have their shank ends 4 securely embedded within the base, while the enlarged head ends 5 of said studs project laterally from the exterior surface of the base and are adapted for engagement with the artificial teeth 6. These teeth may, of course, be of any standard form but in this instance are provided along their lingual surfaces with substantially dove tail shaped securing grooves 7. In practice, these grooves are employed for the reception of anchoring pins which are utilized in securing the teeth in connection with the backings 15 with which they are related in the mouth of the user. In the present instance use is made of these grooves for the purpose of securing them in connection with the mounting 1. It will be observed that the shape of the studs 3 is such that the head end 5 thereof may be slidably received within the enlarged portion of the groove 7, and the tooth advanced on the stud 3 until the head end of the stud comes in contact with the lower closed end 8 of the groove.

To retain the tooth in this position and without liability of injury thereto, I provide the mounting with a plurality of elongated slots or slits 9, which are situated in vertical registration with and immediately below the studs 3. Adapted to be slidably positioned within the slots 9 are headed seating pins 10. These pins are provided with bifurcated shanks 11, struck from a resilient material 35 and so positioned within the slots 9 that the normal resiliency of said shanks will force the latter outwardly so that its surface will frictionally engage with the vertical walls comprising the slot 9, thereby holding the pins 10 in any given position of adjustment within said slots. The headed ends 12 of the pins 10 project beyond the exterior surface of the base 2 and are each provided with a shoulder 13 adapted for engagement with 40 the lower edges of the teeth 6.

In operation, a tooth is positioned upon the stud 3 by locating the open end of the groove in line with said stud while the lingual surface of the tooth is in engagement with the base 2 then, by pushing the tooth upwardly the stud is secured within said groove and upward movement of the tooth limited by the engagement of the stud with the lower closed end 8 of the groove 7. 55 When this is done, the pin 10 is moved upwardly in its respective slot 9 until the shoulder surface 13 thereof comes in contact with the lower end of the tooth. The friction which the shank 11 of the pin exercises upon the walls of the slot 9 is amply sufficient to securely retain the pin in its position of holding engagement in connection with the tooth, thereby preventing the tooth from moving relatively to the stud until after positive operation to this end has been made by

operating the pin. Consideration will disclose that there is no spring pressure on the tooth while the latter is in its secured position and therefore there will be no stresses created within the tooth tending to crack or fracture the same. However, by the mere application of finger pressure to the pin the latter may be adjusted to lock or release the tooth with which it is engaged. By reference to Figure 1 it will be observed that the artificial teeth are, of course, of varying proportions. This is compensated for by reason of the slots 9, which are of sufficient length to allow such adjustment of the pins 10 in order to adapt the latter to teeth of all lengths. This feature is of importance in a practical way in that it enables the teeth to be applied to any of the studs 3 without regard to position or order and the mounting is instantly adapted thereto.

In the form of the invention shown in Figure 5 the shanks 4^a of the stud 3^a are spaced slightly so as to provide maximum resiliency and to thereby enable the shanks to securely and frictionally engage the walls of the slots 9. The shanks are extended to produce curved operating extremities 14 which engage with the lower ends of the teeth 6 and also project to the exterior of the mounting so as to be within the convenient grasp of the operator. It will be apparent that by the use of finger pressure, the extremities 14 may be pressed together so that convenience in the adjustment of the pins may be readily secured.

In the modified form of the invention disclosed in Figures 6 and 7 substantially this arrangement is carried out only in reverse order. In this form of the invention the stud 15 which is employed in connection with the groove 7 of the teeth is adjustable instead of being stationary. This is accomplished by mounting the studs 15 within slots 16 provided in the base 2, and the shanks of said studs are of resilient construction so that the studs will be retained in their set positions of adjustment. Then, the base is provided with stationary outward turned lips 17 against which the lower edges of the teeth 6 engage. This construction is nothing more than a reversal of the arrangement shown in Figures 1 to 4, and the same principles are present and the structure is an obvious equivalent of the showing set forth in the preferred form.

In Figures 8 and 9 a metallic base 18 is used carrying resilient tongues 19 which are stamped out of the base and are provided with crimped or stepped upper ends 20. These tongues provide adjustable stops or shoulders for the reception of the lower ends of the teeth 6, and securely hold such teeth in connection with the securing studs 3 provided on the base 18 without excessive spring pressure or likelihood of injury to

the tooth. Moreover, the structure is adaptable to teeth of varying size. In Figures 10 and 11 resilient heads 21 are pressed out from the base 22 and engage with the lower edges of the teeth mounted upon the base. These heads serve to support the teeth but do not exercise resilient pressure thereon when said teeth are finally applied to the base.

10 In view of the foregoing taken in connection with the accompanying drawings it will be seen that the present invention provides simple yet efficient means for quickly and positively effecting the application or removal of artificial teeth upon or from the base of a mounting. The structure avoids the employment of destructive spring pressure when the teeth are applied upon the base and provides an improved form of 15 fastening device for retaining the teeth in secured positions on the mounting. The mechanism is adapted to teeth of varying proportions, does not require a predetermined placing of the teeth on the mounting, presents an attractive appearance which in no way mars the mounting for display purposes and in addition to these features provides a structure which is simple and 20 convenient to operate and economical to produce.

What is claimed is:

1. A mounting for artificial teeth comprising a base, holding studs on said base, locking members on said base adjacent said studs, and means permitting of relative adjustment between said locking members and studs to effect the securing of a tooth in connection with said base.
2. A mounting for artificial teeth comprising a base, and means for retaining artificial teeth in connection with said base comprising relatively adjustable clamping members mounted on said base, between which said teeth are frictionally secured.
3. A mounting for artificial teeth comprising a base, a tooth holding stud mounted on said base with which an artificial tooth is engaged by sliding movement of said tooth relative to the base, and holding means exercising spring pressure on the base only, said means restraining said tooth from longitudinal movement relative to said stud.

50

4. A mounting for artificial teeth comprising a base, a plurality of tooth holding studs having headed ends carried by said base, the headed ends of said studs being arranged for positioning in the securing grooves of artificial teeth, and a plurality of holding members mounted for sliding adjustment upon said base relative to said studs and cooperative with said teeth to restrain the latter from relative movement with respect to said studs.

55

5. In a mounting for artificial teeth, a base, a plurality of headed studs projecting from said base, artificial teeth having grooves in the lingual surfaces thereof for the reception of the headed ends of said studs, and a plurality of adjustable locking members movable in slots provided in said 60 base and cooperative with said teeth to lock the latter in connection with said studs.

60

6. In a mounting for artificial teeth, a base provided with a plurality of fixed studs having headed projecting ends, the ends of said studs being adapted for engagement with the walls of grooves provided in the lingual surfaces of artificial teeth, locking members adjustable longitudinally of slots provided in said base, said locking members 65 being provided with headed ends arranged for engagement with the lower edges of teeth secured upon said studs, and resilient means formed with said locking members and exercising pressure on the walls of said 70 slots to retain said locking members in set positions of adjustment.

75

In testimony whereof I affix my signature.

LAFAYETTE PICKERING.
